UNITED STATES PATENT OFFICE.

FREDERICK C. OVERBURY, OF MONTCLAIR, NEW JERSEY, ASSIGNOR, BY MESNE ASSIGNMENTS, TO THE FLINTKOTE COMPANY, OF BOSTON, MASSACHUSETTS, A CORPORATION OF MASSACHUSETTS.

METHOD OF MAKING SHINGLE-STRIPS.

1,340,402.

Specification of Letters Patent.

Patented May 18, 1920.

Original application filed March 1, 1915, Serial No. 11,392. Patent No. 1,150,298, dated August 17, 1915.
Divided and this application filed May 14, 1915. Serial No. 28,162.

To all whom it may concern:

Be it known that I, FREDERICK C. OVERBURY, a citizen of the United States, and a resident of Montclair, in the county of Essex and State of New Jersey, have invented certain new and useful Improvements in Methods of Making Shingle-Strips, of which the following is a specification.

This invention has relation to prepared waterproof weatherproof coverings for roofs and side walls, which, when laid, present the appearance of shingles or tiles.

It has heretofore been proposed to manufacture what are termed shingle strips for this purpose by forming in the central part of an elongated sheet of waterproofed felt or like fibrous material a series of transverse slots, and then by severing the sheet along a line longitudinal thereof and interlocking the slots, as pointed out in my Letters Patent No. 908,125, dated December 29, 1908. I have found that, where the shingle strips are thus formed, the strips are apt to bulge and buckle under varying thermal and weather conditions, especially where the strips are relatively long.

The object of the present invention is to provide an improved method of making shingle strips, in consequence of which I am able to prevent the bulging of the strip when laid.

On the accompanying drawing,—

Figure 1 illustrates a sheet of prepared fibrous material and shows how the shingle strips are formed therefrom.

Fig. 2 illustrates one of the shingle strips.

Fig. 3 shows a shingle strip having different shaped tabs.

Fig. 4 represents a section on the line 4—4 of Fig. 2 on a larger scale.

In the manufacture of wool felt, such as I employ for the foundation of my roof covering, the fibers are in the main arranged longitudinally of the length of the strip or sheet, and, in accordance with the present invention, the shingle strips are cut from the sheet along lines transverse to the longitudinal lines of the sheet so that each strip, although it is provided with a plurality of tabs or projections which when laid form the appearance of tiles or shingles, are relatively short, and, because of the arrangement of the fibers transversely of the length thereof, do not bend and

buckle when exposed to varying thermal and weather conditions. The foundation of the strip consists of such wool felt which is saturated or impregnated with the usual waterproofing composition employed in the manufacture of prepared weatherproof roofing, such as pitch, asphalt and the like. The sheet of felt, after being impregnated and saturated with waterproofing compound, is then coated on one or both faces with a weatherproofing coating such as asphalt or pitch of such consistency that it will not run when exposed to solar heat. In some cases, the coating on the outer face of the sheet has embedded therein any suitable mineral material, such as ground or crushed slate or granite or sand, the embedding occurring while the coating is in a soft and plastic state.

In Fig. 3, the impregnated felt is indicated at *a*, the coatings of weatherproof material are indicated at *b* and *c*, and the layer of pressed mineral material is indicated at *d*. After an elongated sheet of suitable width has been thus prepared, it is ready for further treatment in accordance with my invention. Between the side edges of the sheet *e*, I form, by any suitable instrumentalities, a series of pairs of longitudinal slits *f*, *g* which may be spaced apart say for example $\frac{1}{2}$ inch. These slits extend longitudinally of the sheet and are formed in a row across the sheet as shown in Fig. 1. What may be termed the rear ends of the slits are connected by a cross-slit *h*, so that there are formed a series of rearwardly extending tongues *i* which are connected at their front ends to the main body of the sheet. These rows of tongues are separated longitudinally of the sheet, by a distance of say 7 to 10 inches more or less as circumstances may require. Then, by any suitable cutting tool or other instrumentality, the sheet is severed on the dotted line *j*, *j* in Fig. 1, the said line coinciding with the forward ends of the slits *f*, *g*. As a result of this procedure, there is formed a series of shingle strips *k*, each of which is formed at its front or lower edge with a series of tabs or projections *m* separated by slots *n*, with a straight edge *o* defining its upper or rear end. In these strips, the fibers of the impregnated felt extend mainly in lines approximately parallel to the end edges *p*, *p*

of the strips, so that, when the strips are laid in parallel overlapping rows, the tendency to buckle and bend is practically eliminated. In laying the shingle strips upon the roof, each row of strips is overlapped by the succeeding higher row with the shingle tabs or projections m of one row either coinciding with or bridging the upper end of the slots n of the next lower row.

10 It is quite apparent, from the foregoing description, that, by the employment of any suitable cutting instrumentalities, the slits or incisions which are formed in the sheet may be of diverse character, so that the tabs, instead of being substantially rectangular, may be of other shapes, as shown in Fig. 3 for example. It will be understood, of course, that the elongated sheet will be fed forwardly longitudinally of its length, so 20 that, after the successive formation of the rows of slits, the shingle strips are cut successively from the end of the sheet.

Having thus explained the nature of my said invention and described a way of carrying out the same, although without setting forth all the ways in which it may be practised, what I claim is:—

1. The herein described method of making shingle strips, which consists in forming an elongated sheet of flexible felt impregnated with a bituminous waterproofing compound, and severing said sheet transversely into strips each having between its side edges a plurality of tabs or projections 35 of equal width spaced apart to simulate singles or tiles when said strips are laid in overlapping relation.

2. The herein described method of making shingle strips, which consists in forming an elongated sheet of flexible felt impregnated with a bituminous waterproofing compound, and severing said sheet trans-

versely into strips each having between its side edges a straight upper edge, and a lower edge notched to provide a plurality of tabs or projections which are spaced apart approximately one-half inch. 45

3. The herein described method of making single strips, which consists in forming an elongated sheet of felt impregnated with a bituminous waterproofing compound, coated with a layer of bituminous compound and faced with a layer of crushed mineral embedded in said coating, forming in said sheet successive transverse rows of longitudinal slots and severing said sheet transversely on lines intersecting said slots, thereby to form shingle strips each having between its side edges a series of spaced shingle-like tabs of equal width. 55

4. The herein described method of making prepared shingle strips, which consists in forming an elongated sheet of flexible weatherproofed felt, forming a plurality of spaced longitudinal slots in said sheet of greater width than the thickness of said sheet, and then severing said sheet in lines transverse to and intersecting the ends of said slots. 60

5. The herein described method of making prepared shingle strips, which consists in forming an elongated sheet of flexible weatherproofed roofing felt, forming tongues in said sheet by a series of transverse rows of pairs of longitudinal slits and transverse 75 slits connecting the rear ends of each pair of slits, and severing the sheet transversely on lines intersecting the front ends of said pairs of slits simultaneously to cut off the tongues and to form a shingle strip having 80 spaced tabs or projections.

In testimony whereof I have affixed my signature.

FREDERICK C. OVERBURY.
